CARD SHUFFLING AID

Charles L. Shedd, Girardville, Pa.

Application November 29, 1950, Serial No. 13,177

Term of patent 14 years

(Cl. D34—13)

To all whom it may concern:

Be it known that I, Charles L. Shedd, a citizen of the United States and resident of Girardville, in the county of Schuylkill and State of Pennsylvania, have invented a new, original, and ornamental Design for a Card Shuffling Aid, of which the following is a specification, reference being had to the accompanying drawings, forming part thereof.

Fig. 1 is a perspective view of a card shuffling aid embodying my new design;

Fig. 2 is a side elevational view thereof; and Fig. 3 is a top plan view thereof.

On the drawings, the characteristic features of the design are shown in full lines.

I claim:

The ornamental design for a card shuffling aid, as shown and described.

CHARLES L. SHEDD.
